Inventor.

Alphonso Emele,

By *Richard D. Owen.*

Attorney.

UNITED STATES PATENT OFFICE.

ALPHONSO EMELE, OF MARINERS HARBOR, NEW YORK.

SECTIONAL RADIATOR FOR INTERNAL-COMBUSTION ENGINES.

1,254,893.

Specification of Letters Patent. Patented Jan. 29, 1918.

Application filed May 2, 1914. Serial No. 835,887.

To all whom it may concern:

Be it known that I, ALPHONSO EMELE, a citizen of the United States, residing at Mariners Harbor, in the county of Richmond and State of New York, have invented certain new and useful Improvements in Sectional Radiators for Internal-Combustion Engines, of which the following is a specification.

10 My invention relates to improvements in radiators, particularly radiators such as are used on motor vehicles propelled by internal combustion engines, and through which radiators cooling water from the water-jacket 15 or jackets of the engine circulates or passes for cooling.

The invention aims to provide an effective construction of radiator for the purpose set forth, that can be readily cleaned, inspected, or repaired, is capable of manufacture at moderate cost and will prove durable and effective in use.

I find that the foregoing objects can be attained by constructing the radiator of a plurality of cooperating sections and it is one object of this invention to provide a radiator made of a plurality of separate sections removably or detachably fastened together.

20 Another object is to provide a particular construction wherein the joints of the pipes employed may be desirably located and shielded from view to avoid unattractive-ness of the structure.

25 With the above and additional objects in view, the invention has been embodied in preferred form as illustrated in the accompanying sheets of drawings, to be referred to in connection with the following description.

30 In said drawings:

Figure 1 is a longitudinal vertical sectional view of the radiator;

Fig. 2 is a vertical transverse sectional view of the radiator shown in Fig. 1, taken on the line 2—2 of Fig. 1;

Fig. 3 is a detail sectional view illustrating a form of connection for pipes employed in the radiator shown in Figs. 1 and 2.

35 The base section A is in the form of a container, being closed at its sides and ends, the ends, if desired, being provided with short tubes 1 for the withdrawal of water from the radiator. These tubes 1 are provided with screw threads 2 which are detachably engaged by caps 3. From the sec-

tion A, extends inwardly at the top, rest flanges 4. On the rest flanges 4 is seated or rests the bottom or lowermost radiating section. Above the bottom or lowermost radiating section, may be provided any desired number of radiating sections, on the uppermost of which sections, the crown section C rests. Lowermost section B has a flat bottom wall 5 which directly rests on the flanges 4 and this section also has a flat top wall 6. The three uppermost sections B shown are provided with raised bottom walls 7, and at each end with rest walls 8, the rest walls of the section B abutting the lowermost section B rests directly on the wall 6 with the adjacent raised wall 7 distanced therefrom, and the other rest walls 8 are seated or mounted directly on the flat top walls of the uppermost sections B, designated 9. The crown section C has closed side and end walls and inwardly extending rest flanges 10 which directly engage the wall 9 of the uppermost section C. Sections A, B, and C are fastened together in any suitable manner, preferably by means of bolts 11 which extend through the top and bottom and intermediate sections, specifically through the end walls of the section A, the flanges 4, walls 5 and 6, rests 8, walls 9, flanges 10 and the top wall of section C. At the end walls of section A are preferably provided stuffing boxes 12 through which the bolts pass. The bolts are preferably provided with removable nuts 13 at either or both ends. The top wall of section C has a short upstanding water-inlet tube 14 normally closed by a removable cap 15 screw threaded thereto at 16.

Each section B is provided with water circulating tubes 17, which project beyond the walls 6 and 9 of the three lowermost sections. The three uppermost sections B have the tubes flared outwardly below the walls 7 to form bell so as to extend over the projecting upper ends of the adjacent tubes directly therebelow and tightly receive between the outer surface of the projecting ends and the inner surface of flared portions, rubber gaskets 18.

It is of course understood that as automobile radiators are formed of copper, due to its expandable qualities the connections of the tubes constitute expandable joints for forming water tight connections.

In order to shield the joints between the pipes 17 so as to make the structure more

attractive, the raised walls 7 at their front longitudinal edge are deflected and extend downwardly below the walls 9 and 6 of the adjacent sections, forming shield flanges at 5 20, completely concealing the joint. The flanges at the rear are preferably carried downwardly to form a longitudinal rest flange 21 to engage the top wall of the adjacent sections B.

10 If desired, a fastening bolt in addition to the bolts 11 may be employed as at 22, being located at the rear of the radiator and extending through lugs 23 on the bottom and crown sections, and the bolt receiving a removable nut 24. The water circulating through the radiator passes through a system of piping connected to nipples 25, one extending rearwardly from each of the base and crown sections. If desired, any suitable 15 form of grating may be provided on either or both the inner and outer faces or walls of the intermediate sections B and to this end as shown in the drawings, longitudinally, 20 extending fins or bars 26 are provided, 25 having between them spaces for the admission of circulating air to co-act with the pipes 17.

As will be understood, the water enters 30 through one of the nipples 25 and returns through the other nipple 25, passing through the crown section, the tubes and the base section. From the foregoing illustration it will be realized that the sections are removable 35 fastened together and can be readily disassembled for cleaning or other purpose. Further it will be realized that the bolts securely fasten the sections together and that due to the joint formed at the pipe flares 18, 40 leaking of the water is avoided and that also inasmuch as the upper ends of the pipe 17 extend into the flares and are rigid there-

with due to the provision of the gaskets 19, that lateral movement of the sections is prevented.

While I have described and illustrated 45 one form of the invention, it is not to be understood that I limit myself thereto, as changes in the details of construction may be resorted to without departing from the spirit and scope of the invention. 50

I claim:

A radiator for automobiles comprising a plurality of unit sections, a plurality of said sections having raised bottom walls and having rests at their ends, each raised bottom 55 wall being bent downwardly at its front longitudinal edge to form a shield flange; said shield flange being adapted to overlap the top wall of the next adjacent section to shield the top wall of the adjacent section 60 and also constitute a guide for seating the section to which it is attached; said raised bottom wall being bent downwardly to form a rest flange, said rest flange being adapted to rest upon the upper surface of the top 65 wall of the next adjacent section, thus properly spacing said sections, circulating pipes carried by said walls, the upper ends of said circulating pipes projecting above said top walls of a plurality of said sections, gaskets 70 carried on said projecting ends, the lower ends of said tubes projecting below said raised bottom walls and being flared to form bells adapted to receive the gaskets and projecting ends of the tubes of the next adjacent section therebelow.

In testimony whereof I affix my signature in presence of two witnesses.

ALPHONSO EMELE.
